(57) CLAIM

The ornamental design for a handbag with applied metal bow, as shown and described.

DESCRIPTION

FIG. 1 is a front perspective view of a portion of a handbag showing my new design;

FIG. 2 is a right side view thereof;

FIG. 3 is a left side view thereof;

FIG. 4 is a front view thereof;

FIG. 5 is a rear view thereof;

FIG. 6 is a top view thereof;

FIG. 7 is a bottom view thereof;

FIG. 8 is a front perspective view of an alternative embodiment of the portion of a handbag shown in FIG. 1, shown in the environment of a handbag;

FIG. 9 is a right side view thereof;

FIG. 10 is a left side view thereof;

FIG. 11 is a front view thereof;

FIG. 12 is a back view thereof;

FIG. 13 is a top view thereof; and,

FIG. 14 is a bottom view thereof.

The broken lines showing the portion of the bow and a handbag are for the purposes of illustrating environment and forms no part of the claimed design.
